GOLF CLUB CART

Eugene S. Womack, Mexia, Tex., assignor of one-half to George Burkett, Mexia, Tex.

Application January 21, 1952, Serial No. 267,409

2 Claims. (Cl. 280—47.19)

1

The present invention relates to new and useful improvements in golf club carts designed for orderly holding golf clubs while the cart is being wheeled over the ground.

An important object of this invention is to provide a carrier for the golf clubs having individual tubular holders for the respective clubs whereby the same may be kept separated and more readily identified for conveniently selecting and removing a club from the cart.

Another object of the invention is to provide detachable wheels and a handle for the cart and a carrying strap at one side of the golf club holder whereby the latter may be carried, if desired.

A further object of the invention is to provide a golf club cart composed of a frame in which a plurality of tubular golf club holders are positioned for individually holding the golf clubs.

A still further object is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view;

Figure 2 is a rear elevational view;

Figure 3 is a top plan view;

Figure 4 is a vertical sectional view taken on a line 4—4 of Figure 2;

Figure 5 is an enlarged transverse sectional view taken on a line 5—5 of Figure 1 and showing the locking means for the handle;

Figure 6 is a fragmentary vertical sectional view taken on a line 6—6 of Figure 5;

Figure 7 is an enlarged group perspective view of the adjustable means for the wheels; and

Figure 8 is a perspective view of the cover for the cart.

Referring now to the drawings in detail wherein for the purpose of illustration I have disclosed a preferred embodiment of the invention, the numeral 5 designates the frame of the cart generally and which comprises a U-shaped frame member 6 preferably constructed of tubular metal and to the upper ends of which a top plate 7 is welded or otherwise suitably secured, while the lower portion of the frame 6 passes through a bottom plate 8 and is welded thereto so that the

2

lower end of the U-shaped frame member 6 projects downwardly below the bottom plate for a purpose more fully hereinafter explained. An intermediate plate 9 is also welded to the side leg portion of the U-shaped frame member 6 adjacent the lower end of the latter.

The top plate 7 and bottom plate 8 are formed with downwardly extending flanges 10 and 11 respectively to provide a finish and eliminate sharp edges on the plate.

A plurality of tubes 12 are preferably arranged in front and rear rows and may be constructed of heavy cardboard, metal or other suitable material and have their lower ends resting on top of the bottom plate 8 and pass upwardly through openings 13 in the intermediate plate 9 and upwardly through openings 14 in the top plate 7.

A pair of brackets or plates 15 are welded or otherwise suitably secured to the side of the U-shaped frame member 6, immediately below the intermediate plate 9 and to the outer surface of which a disc 16 having a toothed surface is welded or otherwise suitably secured. A threaded pin or stud 17 projects laterally from the disc 16 and on which a second toothed disc 18 is rotatable with the teeth of the discs opposing and held in adjusted position by wing nut 19 threaded on the pin 17.

The toothed disc 18 is on an upper end of an arm 20 which has a stub shaft 21 at its lower end for mounting a wheel 22 thereon, the arm providing a swingable mounting for the wheel to vertically adjust the latter.

The top plate 7 is formed with an upwardly extending socket 23 to removably receive the lower end of a handle 24. A locking pin 25 is slidably carried transversely of the socket 23 and projects outwardly at opposite sides of the socket. The central portion of the locking pin is notched as shown at 26 and is formed with spaced apart teeth or locking dogs 27. Coil springs 28 are positioned on the outer end of the pin 25 and held against heads 29 at the ends of the pin and the inner end of the handle 24 is formed with a longitudinal slot 30 to receive the locking pin 25 when the handle is inserted in the socket 23 and the inner end of slot 30 is formed with a lateral or re-entrance slot 31 in which the dogs or teeth 27 are engaged to lock the handle in the socket.

By pushing the locking pin 25 inwardly at either side of the handle the locking teeth or dogs 27 will be disengaged from the lateral or re-entrance slot 31 and the handle may then be removed from the socket 23.

The arms 20 for wheels 22 may be also be detached from the cart and the frame 5 carried by means of a strap or handle 32 suitably attached to one side of the U-shaped frame member 6.

The tubular holders 12 are adapted for placing golf clubs 33 therein to keep the clubs separated and the lower ends of the holders are provided with pads 34 to protect the handles of the clubs.

A removable cover 35 of suitable waterproof material may be placed over the frame and tubular holders 12, when the device is not in use, and a neck portion 36 is formed at the upper end of the cover to enclose the heads of the golf clubs.

The lower end of U-shaped frame member 6 projects below lower plate 8 to form a prop 37 to support the cart in an inclined position.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described my invention, what is claimed as new is:

1. A golf club cart comprising a U-shaped frame having spaced leg portions and a connecting web, upper and lower plates fixed to the frame, in a position so that the lower end of the frame projects below the lower plate to form a prop, forward and rear groups of tubes supported in a vertical position by said plates in front of and behind the plane of the frame member respectively, and with the lower ends of the tubes closed by the lower plate and the upper ends of the tubes open and adapted to hold individual golf clubs placed therein, wheel mount-

ings attached to the sides of the U-shaped frame, and a handle centrally attached to the upper plate and having a straight portion spaced equidistant from and parallel to said leg portions.

2. A golf club cart comprising a U-shaped frame member including spaced leg portions and a connecting web between the lower ends of said leg portions, a top plate fixed to the upper ends of said leg portions, a bottom plate fixed to the lower ends of said leg portions above said connecting web, a connecting plate fixed to said leg portions intermediate the ends thereof, wheels pivotally adjustably mounted on said leg portions below said connecting plate, a hand grip removably engaging said top plate, a forward group of spaced parallel club holding tubes secured to said connecting, top and bottom plates and having their long axes lying in a plane parallel to and in front of the plane of the frame member, and a rear group of spaced parallel club holding tubes secured to said connecting, top and bottom plates and having their long axes lying in a plane parallel to and behind the plane of the frame member.
